Application August 24, 1938, Serial No. 226,410

7 Claims. (Cl. 30—43)

This invention relates to shaving devices and particularly to shaving devices of the type known as dry shavers which include a thin perforated skin-contacting shear plate and motor-driven cooperating shearing blades which coact with the shear plate to sever hairs that project through the perforations in the shear plate.

In our Patent No. 2,119,021, granted May 31, 1938, and our copending application, Serial No. 210,682, filed May 28, 1938 and patented April 15, 1941, as Patent No. 2,238,278, we have disclosed a shaving device characterized by a convex or dome-like skin-contacting shear plate formed of extremely thin metal and provided with a multiplicity of perforations. The skin-contacting shear plate is adapted to be held against the surface to be shaved and the hairs which project through the perforations in the shear plate are severed by means of comparatively thin blades, which are supported in a member which rotates about an axis normal or perpendicular to the center of the shear plate. The blades are capable of radial and axial movement relatively to the member and are provided with edge portions which cooperate with inclined surfaces on the member in order to urge the blades against the inner surface of the shear plate upon rotation of the member. The comparatively great expanse of the shear plate as compared with the limited area of the blades allows the hairs to project readily through the apertures in the shear plate and are efficiently severed by the rapid movement and action of the cutter blades.

An object of the invention is to simplify the shaving devices described above and to improve the shearing action of such devices.

An object of the present invention is to provide a shaving apparatus in which motion transmitting drives are eliminated, thereby eliminating friction losses and simplifying and increasing the efficiency of operation of the apparatus.

Another object of the invention is to provide a shaving apparatus in which an improved shearing action is produced by utilizing blades having cutting edges which act to sever the hairs cleanly in the manner of a razor blade.

Another object of the invention is to provide shearing devices having shearing blades which automatically adjust themselves to maintain adequate and close shearing engagement with the shear plate under all conditions of operation and which, furthermore, are self-sharpening.

Another object of the invention is to provide shearing devices having cutting blades which tend to draw the hair through the cooperating shear

plate during the cutting action and thereby cut the hair more closely to the skin than has been possible heretofore.

Another object of the invention is to provide shearing devices having vibrating shear plates which cause the hair to project through the shear plate and to be severed close to the skin.

Other objects of the invention will become apparent from the following description of typical forms of devices embodying the invention.

Shaving devices embodying the invention consist of a thin shearing plate shaped as a surface of revolution having a multiplicity of perforations therein, and a motor driven member which is movable through a path of constantly changing angularity about an axis which is approximately concentric with the center of curvature of the shear plate and having one or more guideways or slots therein in which are mounted blades which are free to move into shearing relationship with the under surface of the arcuate shear plate. The blades consist of a body member which has a laterally projecting flange thereon provided with a sharp cutting edge formed at the intersection of the two surfaces, one of which is formed concentrically with the shear plate and the other is inclined at an angle to the shear plate to thereby produce a wedge shaped cutting edge.

More particularly, the invention is embodied in a device which may have either a dome-shaped or an arcuate skin-contacting shear plate with which the blades cooperate to sever the hairs. The blades may take several forms and may either be rigid integral constructions in which the shearing edge portion is formed by bending or otherwise forming the blade into an L or T shaped construction or by attaching a blade portion to the body member by rivets or by pivotal connections whereby the blade may move relatively to the body of the blade to adjust itself into intimate contact with the shear plate.

Because of the wedge-shaped form of the shearing edge in which the inclined surface diverges from the shear plate, upon contact of the shearing edge with a hair, it will tend to wedge and draw the hair into the perforation and, at the same time, sever it cleanly and sharply. Blades of this type, therefore, do not sever hair only by cooperative action of two or more shearing edges as is the case in many types of dry shaving devices, but sever it cleanly with a knife action upon impact of the blade with the hair. Likewise, by disposing the cutting edge at an angle to the main body portion of the blade and mounting the blade in the guide of the support

ing member, there is no tendency for the blade to back off under contact. Instead the blade is retained in its proper cutting position upon contact with and severance of the hair.

Double edged blades of the type embodying the invention are adapted to be used with great efficiency in shaving devices of the oscillatory or rotary type for the reason that the shearing edges are maintained in a proper engagement with the cooperating surfaces of the shear plate. Those blades which have movably mounted cutting edges are particularly adapted for use with the rotary and oscillatory types of shaving devices, for the reason that they conform to changes in position of the main body of the blade as well as changes in contour of the shear plate, thus maintaining uniform shearing contact throughout their entire area.

Because of the uniform contact and the constant tendency of the blade to move outwardly during operation of the shaving device, the blades are substantially self-sharpening, since normal wear on the contacting surface renews the keenness of the cutting edge without varying the angular relationship between the surfaces which intersect to form the cutting edge.

Shaving devices embodying the invention may be reduced to the simplest form by utilizing a shear plate associated with the fixed armature of a motor and by providing the rotor of the motor with guides for receiving the blades. The shearing plate and the rotor preferably are concentric and therefore, upon rotation of the rotor, the movably mounted cutting blades are urged outwardly into engagement with the inner surfaces of the shear plate to obtain the proper shearing engagement therebetween. This type of construction does not require motion transmitting mechanisms in order to actuate the blade supporting member. A quiet running and efficiently operating device therefore, can readily be manufactured. The shear plate may be associated in any desired way with the fixed armature of the motor. Preferably it is made in the form of a cylindrical tube of non-magnetic material which will, therefore, not affect the magnetic field of the motor. Such non-magnetic alloys as copper-beryllium alloys may be used, if desired. However, the operation of the motor is not materially altered even when a steel shearing plate is used, for the reason that its thinness and perforations reduces its mass so as to alter the magnetic field only within the working limits desired.

Any of the devices described above may be provided with means for imparting a vibratory or oscillatory or gyratory movement to the shear plate in order to cause the shear plate to work over the face and by repeated impact to cause the hair to be projected through the perforations in the shear plate. The vibratory movement has been found to be effective in assuring close severance of the hair and improving the shearing action of the devices.

For a better understanding of the present invention, reference may be had to the accompanying drawings, in which:

Figure 1 is an end view of a typical form of shaving device embodying the invention with the shear plate partly broken away to disclose details of the cutting mechanism;

Figure 2 is a side view of the device disclosed in Figure 1, shown partly in section and partly broken away;

Figure 3 is a perspective view of a blade, greatly enlarged, embodying the invention;

Figures 4, 5 and 6 are perspective views of modified forms of blades;

5 Figure 7 is a view in vertical section of another form of shaving device embodying the features of the invention;

Figures 15 and 16 are plan views of counterbalancing devices for a cutter member; and

30 Figure 17 is a sectional view of a cutter member with the counterbalancing devices applied thereto.

In Figures 1 and 2 of the drawings is disclosed a shaving device of the type described more particularly in our copending application, Serial No. 210,682, filed May 28, 1938. This shaving device 35 consists of a handle 10 in which is mounted an electric motor, not shown, for actuating a supporting or cutter member 11, which is fixed by means of a set screw 12 to the upper end of the shaft 13 of the motor. The cutter member 11 is provided with a rim 14 having a conical inner surface 15 against which bear the inclined edges 16 of a plurality of blades 17. The blades 17 are received in radially extending slots 18 in the cutter member 11 and are capable of axial as well as radial movement during rotation of the cutter member 11, whereby engagement of the edges 16 of the blades 17 with the conical surface 15 will cause the cutting edges of the blades to move into intimate engagement with the under surface of a shear plate 19. The shear plate 19 is of dome or convex shape and is supported at its periphery in a collar 20 which is detachably connected to the upper end of the handle by means of pin and bayonet slot connections 21. The blades are retained on the supporting member 11 by means of a spring ring 22 which is received in an undercut groove 23 formed in the upper surface of the supporting member 11.

Upon rotation of the supporting member 11, the centrifugal force generated urges the blades 17 radially outwardly and upwardly because of the engagement of the edge portion 16 with the conical surface 15, thereby forcing the edges of the blades against the under surface of the shear plate 19 in shearing relationship.

The blades indicated generally as 17 may take many different forms. In order to obtain the most efficient and rapid shearing action they are provided with a laterally extending portion which 70 forms a keen cutting edge on one or both sides of the blade. Referring to Figure 3, a blade 17 is shown, which consists of a body portion 24 having an aperture 25 therein for receiving the spring ring 22 and a widened blade portion 26 having 75 oppositely directed longitudinally cutting edges

27 and 27' thereon. The blade portion 26 is shaped to conform to the under surface of the shear plate 19 and therefore is curved longitudinally. The under surface of the blade portion 25 is formed by inclined surfaces 28 and 29, which intersect the curved surfaces to form the wedge shaped cutting edges 27 and 27', respectively. The inclination of the under surfaces 28 and 29 with respect to the upper surfaces may vary between about 22 and 68° while an inclination of about 30° has been found to be entirely satisfactory. This type of blade may be used with equal facility with a rotary type of shaving device or an oscillatory type, for the reason that a surface of substantial width is provided, which maintains the cutting edges 27 or 27' in proper relationship to the shear plate and they therefore, can cut with equal effectiveness in either direction of movement of the supporting member.

A double-edge type of blade is disclosed in Figure 4. This blade consists of a body portion 30 having an aperture 31 therein for receiving a retaining ring. Oppositely directed shearing edges 32 and 33 are formed on the upper portion of the body member, imparting to it a generally T-shaped cross section, and these edges are separated by a longitudinally extending groove 34 which reduces the area of contact between the blade and the shear plate.

The form of blade disclosed in Figure 5 is provided with a single shearing edge portion 35 which projects laterally from the body 36 of the blade. The shearing edge portion 35 may be formed by bending the upper edge of the blade and honing the upper surface 37 to produce a keen laterally extending cutting edge 35'. Likewise, the blade may be preformed and then honed or lapped to produce the cutting edge.

The modified form of the blade disclosed in Figure 6 may also be used with equal facility in a rotary type of razor. This blade consists of a strip of metal 38 which is bent along a longitudinal line 39 to form diverging portions 40 and 41 having a relative inclination of about 120°. The blade portion 41 is provided with a cutting edge 42 which is formed by lapping or honing the upper edge of the blade. The blade portion 40 and the apex portion formed along the bending line 39 engage opposite sides of the guide slot 18 and thereby position it for radial and axial movement relatively to the guideway.

A modified form of shaving device is disclosed in Figures 7 and 8, which operates similarly to the shaving device disclosed in Figures 1 and 2. The shaving device disclosed in Figures 7 and 8 consists primarily of an electric motor of any desired type, such as for example, squirrel cage, A. C.—D. C., or make and break contact motor of the type ordinarily used in electric shaving devices. The motor suitably consists of a fixed field 50, which is mounted in any desired way in a handle casing 51 and which has its pole portions 52 and 53 disposed adjacent the upper portion of the casing 51. The motor is shown somewhat diagrammatically, for the reason that the specific type of motor is not a feature of this invention, any suitable type of motor being satisfactory. Between the opposed pole portions 52 and 53 of the field 50 is mounted a cylindrical shell 54 having a multiplicity of perforations 55 in the outermost portion thereof to allow hairs to pass into the interior of the shell. The shell or shear plate 54 preferably is formed of some non-magnetic material such as copper-beryllium alloy, although, if desired, it may be formed of any other

thin metal since the magnetic field is not altered unduly by the presence of this thin metal. The shell 54 may be anchored in position by lugs 56 projecting from the pole portions 52 and 53 into apertures 57 in the shell 54. If desired, the shell 54 may be formed of a plurality of sectors which may be anchored to the field 50 or the casing in any desired way. The shell 54 may be reinforced and retained in the casing by arcuate bands 58 which extend over and embrace the end of the shell. Mounted concentrically in the shell 54 is the rotor 59 of the motor which cooperates with the fixed field 50. The rotor 59 is provided with radially extending slots 60 or guiding devices which receive any type of shearing blades such as 61. The blades 61 are movable radially of the slots, and therefore are urged outwardly into engagement with the inner surface of the shell 54 by rotation of the rotor. As shown particularly in Figure 8, endwise movement of the blades is prevented by means of end plates 62 which are screwed or otherwise fixed to the end of the rotor 59. It will be understood that the shaft 63 which supports the rotor may be journaled in suitable bearings in the end portions of the motor or casing 51. Apertures (not shown) may be provided in the ends of the casing 51 and communicating with the interior of the shell 54 to allow removal of the severed hair.

In operation, the rotor 59 revolves at high speed, and the centrifugal force generated by rotation thereof urges the blade 61 directly radially outwardly into contact with the inner surfaces of the shell 54, thereby wiping the blades rapidly across the perforated portion of the shell and severing hairs which project through the perforations 55.

Blades of the type previously described may be used in this type of shaving device, the only modification being the provision of straight shearing edges and a generally rectangular body instead of curved edges, and a generally trapezoidal body.

In Figure 9 is disclosed a T-shaped blade which may be used to particular advantage in the type of shaving device disclosed in Figures 7 and 8. This blade consists of a body portion 65 of flat rectangular shape which has mounted on its upper edge a concavo-convex blade 66 having oppositely directed shearing edges 67 and 68. The blade portion 66 is loosely connected to the body portion 65 by means of pins or rivets 69 which allow a limited rocking movement of the blade portion 66 with respect to the body 65 thereof.

The T-shaped blade shown in Figures 10 and 11 is similar to the blade disclosed in Figure 9. This modified form of blade consists of a generally rectangular flat body portion 70 having upwardly projecting arms 71 which are provided with inwardly directed pivot portions 72. Oscillatably mounted on the pivot portions 72 is a blade member 73 formed of thin metal which is bent to provide a substantially tubular center portion 74 and outwardly projecting wings 75 having cutting edges thereon. The pivot members 72 are received in the tubular or socket portion 74 of the blade portion 73, thereby retaining it against longitudinal and transverse movement but allowing relative oscillatory movement between the blade portion and the body portion 70.

The forms of the blades disclosed in Figures 9, 10 and 11 are particularly useful in conjunction with shaving devices having cylindrical shearing plates for the reason that they can adjust themselves to any variations in curvature of the shear

plate. Likewise, these blades are reversible and thereby have substantially twice the cutting life of the ordinary single edge blades. Also, these blades are self-sharpening, for the reason that as the blade portion wears away, very little if any change in the angular relationship between the surface forming the shearing edge occurs.

The form of device disclosed diagrammatically in Fig. 12 includes features that are present in the forms of devices disclosed in Figs. 1, 2, 7 and 8. The device disclosed in Fig. 12 includes a dome-shaped shear plate 80 detachably supported on the upper end of the handle casing 81. Within the casing is a motor consisting of pole or field pieces 82 and 83 between which is rotatably supported the rotor 84 which has its axis extending longitudinally of the casing 81. The rotor 84 has a central bearing aperture 86 which receives a shaft 87. The shaft 87 is fixed to a non-magnetic cross-piece 88 extending between 15 and fixed to the pole pieces 82 and 83.

The upper end of the rotor 84 in Fig. 12 is provided with a cutter member 89, similar to member 11 disclosed in Figures 1 and 2, and carrying the blades 90, which may be any of the forms described, such as that illustrated in Fig. 5, for example.

Upon energization of the field pieces 82 and 83, the rotor 84 rotates causing a shearing action to take place between the blades 90 carried by 30 the cutter member 89 and the shear plate 80.

It has been found by experimentation on the hair of various individuals that an improved shearing action may be obtained in many instances by imparting a vibratory or gyratory movement to the shear plate. Apparently the movement of the shear plate causes the hairs to be worked into the perforations of the shear plate and to be extended a greater distance from the skin, thus allowing the hair to be severed 40 closer to the skin.

In Figures 13 and 14 is shown a modified form of the blade-supporting part 91 of a cutter member 11 with the blades omitted, this part 91 being drilled or otherwise formed to be mechanically unbalanced, whereby upon rotation the entire shearing device will vibrate and cause the associated shear plate to work over the skin. As illustrated, an aperture 92, formed as by drilling, is directed radially of the part 91. However, any other means may be used for unbalancing the cutter member.

A variable effect unbalancing construction is shown in Figs. 15 to 17. This construction consists of a pair of like disks 93 and 94, provided with cutouts 95 and 96, respectively. These disks may be fixed beneath the cutter member 97 in any desired relative positions. By placing the cutouts 95 and 96 in alignment, the greatest amount of unbalance is obtained, and by varying their relative positions, the unbalanced state may be decreased until they are accurately counterbalanced as shown in Fig. 17.

Shaving devices of the type described above utilizing the form of blades disclosed in Figures 1 to 6 and 9 to 11, shave rapidly and with a minimum of razor pull. The reason for this is that a true cutting action takes place because of the keenness of the cutting edge, and scraping of the hairs with its consequent pulling is entirely avoided. Preferably the blades should be made as keen as practicable by reducing the angle between the surfaces forming the shearing edge.

It will be understood that there can be many changes made in the form of the shear plate and

the configuration of the blades without departing from the invention. Therefore, the above described embodiments of the invention should be considered as illustrative and not as limiting the scope of the following claims.

We claim:

1. In a shaving device, the combination of a thin shear plate having a curved surface formed as at least a part of a surface of revolution and having a multiplicity of perforations therein, a blade supporting member movable about an axis coincident with the axis of revolution of the shear plate, at least one guide on said member extending substantially radially to the axis of movement thereof, a blade in and movable radially of the guide into cutting engagement with said shear plate in response to movement of said member, said blade comprising a body member maintained and movable in substantially constant angular relationship to said member, and a portion extending laterally from said body member in the direction of movement of said blade supporting member and having a sharp cutting edge formed by at least two intersecting surface portions, one of which engages and is symmetric with the shear plate and the other is inclined at an angle thereto.

2. In a shaving device, the combination of a thin perforated shear plate, a blade supporting member movable relatively to said shear plate and having a slot arranged transversely to the general direction of movement of the member, a blade body relatively loosely mounted in said slot, and a double-edged blade relatively loosely mounted on said body with its opposite edges wiping the under-side of said shear plate during movement of said member for cooperation with the perforations therein to sever hairs projected therethrough, one of said edges acting as a guide for the other edge to maintain the latter in cutting relation with the edges of the perforations in the shear plate.

3. In a shaving device, the combination of a thin, perforated, curved, shear plate formed as at least a part of a surface of revolution, a blade support movable about an axis substantially coincident with the axis of revolution of said shear plate, said blade support having a slot arranged substantially radially of the said axis and transversely of the direction of movement of the support, and a substantially flat blade loosely inserted in said slot at one side with its free side extending toward said shear plate for engagement therewith as the blade is urged radially outwardly in said slot by centrifugal force during movement of said blade support about its axis, said free side of said blade being provided with opposite cutting edges disposed substantially transversely of the direction of movement of the blade during a shaving operation for cooperation with the perforations in the shear plate to sever hairs projected therethrough, said cutting edges projecting outwardly beyond the adjacent portion of said blade.

4. In a shaving device, the combination of a thin shear plate formed as at least a part of a surface of revolution having a multiplicity of perforations therein, a blade supporting member movable about an axis coincident with the axis of revolution of the shear plate, at least one guide on said member extending transversely of the direction of movement of said member, a blade loosely disposed in and movable radially in the guide into cutting engagement with said shear plate in response to movement of said member,

said blade comprising a body member and a blade portion having oppositely directed shearing edges mounted at an edge of the body member for rocking movement relatively thereto, said shearing edges being formed by at least two intersecting surface portions, one of which engages and is symmetric with the shear plate and the other is inclined at an angle thereto.

5. In a shaving device, the combination of a thin shear plate formed as at least a part of a surface of revolution having a multiplicity of perforations therein, a blade supporting member movable about an axis coincident with the axis of revolution of the shear plate, at least one guide on said member extending substantially transversely of the direction of movement of said member, a blade loosely disposed in and movable radially in the guide into cutting engagement with said shear plate in response to movement of said member, said blade comprising a body member having inwardly projecting pivot portions adjacent its ends and a thin curved blade portion having oppositely directed shearing edges and sockets in its ends for receiving said pivot por-

tions, said shearing edges being formed by at least two intersecting surface portions, one of which engages and is symmetric with the shear plate and the other is inclined at an angle thereto.

5. A blade for a shaving device comprising a thin substantially flat blade body portion having an elongated upper edge, a cutting edge portion extending longitudinally of said body portion adjacent said elongated edge, said cutting edge portion having oppositely directed cutting edges projecting outwardly beyond the sides of said body portion, and means connecting said blade portion to the body portion for relative rocking movement.

15 6. A blade for a shaving device comprising a thin substantially flat blade body member, inwardly projecting pivot portions adjacent the ends of said body member, and a thin blade portion having oppositely directed shearing edges and sockets in its ends intermediate said shearing edges for receiving said pivot portions.

FREDERICK E. MOSKOVICS.

VICTOR R. ABRAMS.
